UNITED STATES PATENT OFFICE.

HOWARD W. FLEMING, CHARLES A. RISSE, AND ORRIS K. WEBB, OF SAN JOSE,
CALIFORNIA.

CAMP BED.

Application filed February 10, 1923. Serial No. 618,357.

To all whom it may concern:

Be it known that we, HOWARD W. FLEMING, CHARLES A. RISSE, and ORRIS K. WEBB, citizens, respectively, of the United States, 5 and residing at San Jose, in the county of Santa Clara and State of California, have invented certain new and useful Improvements in Camp Beds, of which the following is a specification.

10 Our invention relates to a form of bed that may be quickly assembled and disassembled, and that may be packed in small space for transportation as on the running board of an automobile.

15 It is the object of our invention to provide a bed of the character indicated that is light in weight, collapsible into a small compact bundle, strong and durable, economical to manufacture, quickly assembled 20 and disassembled, and one that will properly sustain bodies placed thereon.

In the drawing,—

Figure 1 is a plan view of a bed embodying our invention.

25 Figure 2 is an enlarged sectional view on 2—2 of Figure 1, parts being broken away.

Figure 3 is a side elevation of the figure shown at 1.

30 Figure 4 is an end elevation with legs collapsed.

Figure 5 is an enlarged detail of a portion of the supporting mesh shown in Figure 1.

Referring more particularly to the drawing, 1—1 indicate the two side bars of the 35 frame fitted with end pins 2—2—2—2, and brace engaging pins 3—3—3—3. At 4—4 are shown end bars, each bar 4 having an orifice at 5 to receive a pin 2, and having legs 6—6 mounted thereon as shown by 40 hinges 7—7. By this construction the legs 6—6 fold flat against end bars 4 when not in use. On each leg 6 are pivotally mounted braces 8—8 as at 9—9, these braces, when in an operative position, engaging pins 3 45 and 9 respectively as shown whereby to maintain the frame in a rigid position when assembled.

50 The fabric supporting the weight of the sleepers is composed of light rope 10, woven together to form a coarse mesh as shown, each intersection being secured against relative movement of the two crossed rope parts by means of metallic clasps 11.

In the form shown, one portion of the 55 rope is woven back and forth laterally as at 12 and formed into side loops 13 proportioned to hold the whole fabric taut from side to side when mounted on side bars 1—1. The longitudinal portions 14 of the 60 rope are also provided with terminal loops 15, but these loops only approach but do not reach end bars 4—4.

Attached to the fabric at each end as at 65 16 are ropes 17. In assembling the bed after the frame is erected with side bars 1—1 passing through loops 13, one rope 17 is passed alternately around the adjacent end bar 4 and the adjoining loops 15 and finally tied to end bar 4 as shown at 18. The other rope 70 17 is then passed around the other end bar 4 and through the other end loops 15 and tightened up in such a manner as to hold the fabric taut longitudinally and tied as at 19.

75 The structure is collapsed by untying the ropes 17 and pulling them out of engagement with their respective loops and end pieces, collapsing the frame by disengaging the several braces, separating the end bars from the side bars and rolling the side bars and fabric up into a bundle. The end bars are then added to the bundle and the whole tied with the ends of the ropes 17.

80 It may be readily seen from the foregoing 85 that the bed constructed as set forth has all the desirable features set forth. It is not only exceedingly light and strong but provides sufficient resilience to make a comfortable bed, and the fabric will not give unduly so as to roll the occupants to the center of the bed. The resiliency is secured partly by a slight bowing of the side bars 1—1 when a weight is placed on the fabric.

90 It should also be pointed out that in this 95 construction the end bars are interchangeable, so that no time is lost in selecting a particular part to go in a given place.

As an additional strengthening and supporting element, a piece of rope of larger 100 diameter than that used in the fabric itself may be inserted as at 20 and provided with an end loop 21 attached to end bars 4—4 as shown.

105 It is to be understood, of course, that while we have herein shown and described one specific embodiment of our invention,

changes in form, construction and method of application may be made within the scope of the appended claim.

We claim:—

5. In combination, a frame having separable side and end members, a fabric composed of a plurality of flexible elements arranged in spaced parallel relation to each other and provided with terminal loops, flexible elements attached at one end only to opposite ends of said fabric and adapted to alternately engage the adjacent end members of
- 10

said frame and one of said loops and then secured to said end member, a second series of spaced parallel flexible elements arranged transversely of said first elements and forming terminal loops slidably engaging the side members of said frame, and means for securing the two sets of elements together at their intersections. ¹⁵
